UNITED STATES PATENT OFFICE.

BENJAMIN PLOWMAN KENT, OF OUTLOOK, SASKATCHEWAN, CANADA.

MACHINE FOR HULLING WHEAT.

Application filed June 27, 1924. Serial No. 722,833.

To all whom it may concern:

Be it known that I, BENJAMIN PLOWMAN KENT, a subject of the King of Great Britain, and resident of the town of Outlook, in 5 the Province of Saskatchewan and Dominion of Canada, have invented certain new and useful Improvements in Machines for Hulling Wheat, of which the following is a specification.

10 This invention relates to improvements in machines for hulling wheat and the objects of the invention are to provide a machine of this character that will leave the wheat practically free from creasedirt, fuzz 15 and outer fibre, and in better condition to go to the rolls.

Still further objects are to provide a machine of this character of efficient and durable construction that can be manufactured 20 and placed on the market at a reasonable price and generally better adapted to perform the functions required of it.

With the foregoing and other objects in view, my invention relates to a machine 25 adapted to be used for the preparatory treatment of wheat after it has been thoroughly cleaned, and before going to the rolls for reduction to flour.

The machine consists essentially of an 30 outer casing having a shaft centrally mounted therein on which a drum of rotary milling blades is carried, means being also provided for admitting water to the machine to temper the wheat and also means for discharging 35 the whole product after being operated upon by the machine.

Referring now to the drawings in which like characters of reference indicate corresponding parts in each figure,

40 Figure 1 is a side elevation.

Figure 2 is a top plan view.

Figure 3 is an end view.

Figure 4 is a longitudinal section.

45 Figure 5 is a section on line 5—5 of Figure 4.

Figure 6 is an end view of the rubbing plates on end of drum.

Figure 7 is a plan view of one of the hulling blades.

50 Figure 8 is an enlarged section through one of the rubbing plates.

In the drawings 10 designates the head or end casting of the machine provided with a feed opening 11 to which is attached a feed 55 spout 12. 13 is the other casting which is in all respects similar to the casting 10, both

being provided with suitable legs 14, adapted through openings 15 to be secured in position.

Supported by these castings in an outer 60 casing 16 having centrally arranged therein a longitudinally extending shaft 17 provided with a driving pulley 18 at one end. It will thus be seen that the two castings form respectively one half the frame of the machine 65 and are so formed as to accommodate the shaft 17 journaled therein, and provided with suitable caps 19.

The outer casing 16 is preferably made of heavy galvanized iron and when in place 70 its ends lap over circumferential flanges on castings 10 and 13, all being securely held by four horizontal rods thus completing the frame.

A water intake 12^a is also provided in the 75 form of a conical raised opening which may be provided with a grating or the like for the water to pass through before it enters the machine. The casing 16 is also provided with a discharge spout 16^a of galvanized 80 iron or other suitable material and adapted to carry the wheat, after it is crowded up from the rubbing plates by the centrifugal force of the milling drum. At the top of the spout is attached a hinged lid 9, a heavy 85 member and perfectly flat to close the discharge spout opening entirely. This lid is controlled by a spring 8 which has an adjustable screw 7 to govern the pressure in operation and on the shaft being rotated the 90 wheat is delivered through the hopper first. On the casing being charged and the water being admitted through the intake 12^a the wheat passes to the hulling blades and from them to the rubbing plates arranged on the 95 outer discharge end of the hulling drum and also on the discharge end casting, registering with said plates on the outside of the discharge end of the hulling drum, then as the wheat is operated upon by these plates 100 it is delivered by the centrifugal force exerted by the hulling drum to the discharge spout 16^a.

Within the machine and on the shaft 17 is fixedly mounted a hulling drum 22 comprising two heavy cast flanged hub collars 23 with set screw 24 for attaching the drum solidly to the shaft 17, and on these flanges are securely riveted the boiler plate ends 25 of the drum. On the outside of the discharge end of the hulling drum 22 are mounted a set of rubbing plates 26. The 110

head end plate of the hulling drum is similar to the discharge end except that rubbing plates are provided on the outer surface of the discharge end.

5 The hulling blades 27 are preferably made of heavy, woven, scouring case material and consist of two pieces, securely riveted together to make one blade. The cutting surface of the blades is on the outer side and 10 their outer edges come in direct contact with the crease of the wheat berry as it circles endwise around the drum. The rubbing plates, on the other hand, are made from pressed steel sheets, and formed with faces 15 having saucer-shaped indentures, therein.

In use and as illustrated in Figure 4, a plurality of hulling blades are carried in the hulling drum, slightly spaced from one another and are hung in sets preferably 20 about an inch apart on two horizontal rods 30 and 31 and are divided by cast iron washers 32. At each end of these rods is a nut 24^a and by operating these nuts the points of the hulling blades may be moved to 25 right or left. When moved slightly to the right it will cause the wheat to become much deeper between and around the hulling blades before travelling on to the rubbing plates at end of drum. When moved slightly 30 to the left exactly the reverse will happen, and the hulling action will be less severe. This constitutes the adjustable feature of 35 the hulling drum and is most important.

As many changes could be made in the 40 above construction and many apparently widely different embodiments of my invention, within the scope of the claims, constructed without departing from the spirit or scope thereof, it is intended that all 45 matter contained in the accompanying specification and drawings shall be interpreted as illustrative and not in a limiting sense.

What I claim as my invention is:

1. A machine for hulling wheat, comprising 45 a suitably supported outer casing, a ro-

tatable shaft journalled through said casing, a driving pulley on said shaft, a hulling drum within the casing and fixedly mounted on said shaft, a plurality of hulling blades on said drum, rubbing plates on the 50 end of said drum and rubbing plates registering therewith on the inner end of the casing, intake and discharge means for the casing, means for adjusting the hulling blades and water intake means in the casing. 55

2. A machine of the character described, comprising a pair of castings, an outer casing supported by said castings, a shaft through said casing and supported by said castings, an intake hopper in one of said 60 castings and a discharge spout in the casing, and a water intake in the casing, rubbing plates carried by one of said castings, a hulling drum comprising a plurality of spaced, adjustable hulling blades carried by 65 said shaft within the casing and means for rotating said shaft.

3. In a machine as described in claim 2, in which the hulling blades are formed in two sections mounted on rods in spaced relationship to one another and having washers therebetween and adjusting nuts on said rods whereby the blades are moved apart or close 70 together.

4. In a machine as described in claim 2, 75 a plurality of rubbing plates fixedly mounted on the outer end of the hulling drum and similar plates adapted to register with the afore-mentioned plates on one of said castings, whereby on the wheat passing 80 from the hulling blades it is operated upon by said rubbing plates.

5. In a machine of the character described in claim 2, a hulling blade of woven material formed of two pieces riveted together and 85 having a cutting surface on the outer side adapted to fit around a hulling drum.

In witness whereof I have hereunto set my hand.

BENJAMIN PLOWMAN KENT.
